UNITED STATES PATENT OFFICE.

ARTHUR J. KERCHER, OF BERKELEY, AND WILLIAM WESLEY HICKS, OF SAN FRANCISCO, CALIFORNIA.

ELECTRIC AIR HEATER.

Application filed September 16, 1926. Serial No. 135,927.

This invention relates generally to electrical devices for heating air within a room.

In permanently installing electrical air heating equipment for domestic purpose it has been customary to employ either a heater of the wall type such as disclosed in the patent to W. W. Hicks, No. 1,518,067, or a floor type heater such as disclosed in the patent to Kercher and Hicks, No. 1,534,221.

When these heaters are installed subsequent to the erection of a building, material alterations are required and inconvenience is often experienced in providing wiring which will carry the relatively heavy current load.

It is one object of this invention to devise a novel form of electric air heater which may be readily installed in a room in place of a hot air heating system of the fuel burning type.

It is a further object of this invention to devise an air heater in which the air of the room is continuously circulated into contact with electrical heating elements but which is constructed in such a manner as to permit positioning of the heater elements a substantial distance below the floor of the room.

Further objects of the invention will appear from the following description in which we have set forth the preferred embodiment of our invention. It is to be understood that the scope of the invention is to be determined from the appended claims and the state of the prior art.

Referring to the drawings:

Figure 1 is a cross sectional elevational view showing an air heater constructed in accordance with this invention.

Fig. 2 is a view similar to Fig. 1 showing a modified construction of air heater.

Fig. 3 is a cross sectional view similar to Fig. 1 showing a further modification.

The invention comprises generally the use of an electrical heating element located a substantial distance below the floor of a room to be heated. An air register is provided in the wall or floor of the room and is connected with the heating element by means of a plurality of passageways, one passageway serving to conduct heated air from the heating element to the room and another passageway serving to conduct an induced downwardly moving draft of cool air from the room to the heating element. In this way air within the room is continuously circulated into contact with the

heating element. Thus referring to the drawings there is shown a register 10 in the form of a foraminated grill located flush with the wall 11 of a room to be heated. Located a substantial distance below the floor 12 of the room there is a housing 13 which is adapted to inclose one or more electrical heating elements 14. The housing 13 for example may be supported upon the floor 15 of the basement below the room to be heated.

Currents of air from the room are circulated through the housing 13 through the use of a suitable conduit 17 which connects the register 10 with the housing 13. In order to separate the upwardly moving current of air from the downwardly moving cool current the conduit 17 is constructed to provide a plurality of passageways. For example, there is shown an inner pipe 18 within the conduit 17 to provide an inner passageway 19 for an upwardly moving air current and an outer passageway 20 for a downwardly moving air current. The heating element 14 is associated with the lower portion of the passageway 19 in such a manner as to receive air drawn downwardly through the passageway 20, and after heating the same, to discharge the heated air into the lower portion of the inner passageway 19.

The particular construction of the housing 13 shown in Fig. 1 comprises an outer shell 22 having an open front 23 and a forwardly extending top wall 24. Within this outer shell there is an inner and substantially smaller shell 26 which is similarly provided with a forwardly extending top wall 27. The upper forward edges of the walls 24 and 27 are secured respectively to the corresponding edges of conduit 17 and pipe 18 whereby a portion of passageway 20 is continued to passageway 28 formed by the spaced relationship of shells 22 and 26.

The heating element 14 has been shown as being mounted upon the bottom shelf 29 of the inner shell 26 and may be constructed for example in the form of a hollow refractory core 30 having wound upon its periphery a suitable resistance conductor 31. A heating element of this sort forms a flue 32 for convection currents of air and in this particular case the flue 32 is in communication with the air below the shelf 29, this shelf being provided with one or more aper-

tures registering with the flue 32 of each core. Along the junction between the inner pipe 18 and the inner shell 26 the lower edge of the pipe 18 may be cut away to provide an 5 opening 33 to allow convection currents of air to come into contact with the outer surface of the resistance element 14.

In operation air coming into contact with the heating element rises upwardly within 10 the passageway 19 and is discharged into the room. At the same time a downwardly moving current of air is induced in the passageway 20, thus drawing cool air from the room and discharging the same through the flue 32 15 of the heating element and through opening 33, as shown by the arrows. In this way a continuous circulation of air is established so that the thermal frequency of the system will be relatively high. In order to control 20 the amount of heated air being discharged into the room the register 10 may be provided with a suitable damper controlled as by means of a hand lever 36, this damper serving to interrupt the discharge of heated 25 air into the room. A temperature responsive switch 37 may also be provided within the housing 13 to interrupt the current supplied to the heating element in case the temperature of the air reaches a certain pre-determined maximum. Suitable heat insulating material 38 may also be placed upon the outer surfaces of the conduit 17 and the 30 housing 13.

The modification shown in Fig. 2 is similar 35 to that described above but differs with respect to the arrangement of the heating elements within the housing 213. In this case the heating elements 14 are shown as being mounted directly below the lower end of the 40 inner pipe 118. Thus one or more heating elements 14 are shown as mounted upon a suitable bracket 40 whereby they are spaced from the bottom wall 41 of the housing 213. These elements are also surrounded by means 45 of an inner casing 42 which is joined to the lower end of the inner pipe 118. The space between the inner casing 42 and the outer housing 213 serves to define a passageway 43 communicating with the passageway 120 of 50 the conduit 117, and since the casing 42 terminates short of the bottom wall 41, the passageway 43 is in communication with the interior of the casing 42. Air heated by the heating elements 14 is accordingly discharged upwardly through the inner passageway 119 and a downwardly moving draft of air is induced in the passageway 120, the air circulating downwardly through this passageway, through passageway 43 and 55 up through the flues 32 of the heating elements and into contact with the outer surfaces of the same. Additional baffle walls 44 may also be disposed between the casing 42 and the outer housing 213 in order to prevent undue heating of the outer housing.

In the modification shown in Fig. 3 the conduit 317, instead of being divided into concentric passageways, is divided into two passageways by means of an intermediate partition 46, this partition serving to define 70 a passageway 47 for downwardly moving currents of air and a passageway 48 for upwardly moving currents. The housing 313 for inclosing the heating elements 14 is provided with a dividing or baffle wall 49 75 serving as an extension of the central partition 48 of the conduit 317. The baffle wall 49 serves to define within the housing 313 a compartment 50 within which is arranged the heating elements 14, and a compartment 51 which communicates with the passageway 47 adjacent its upper end and communicates with compartment 50 adjacent its lower end. Thus air heated within the compartment 50 by the heating elements is caused to be discharged into the room through passageway 48, while cool air is caused to flow downwardly from the room through passageway 47 and into the bottom of the compartment 50. As with the construction previously described, the conduit 317 and the housing 313 may be provided with suitable heat insulating material 52 and similar material 53 may be applied to the intermediate partition 46.

For purposes of ventilation it is frequently desirable to introduce a limited amount of fresh air into the device. Thus in Fig. 1 there is shown a conduit 50 communicating at its one end with a supply of fresh air and at its other end with passageway 20. The amount of fresh air introduced is controlled by means of a damper 51 and rod 52, the rod projecting through the grill or register 10.

The installation of a heater of this type necessitates practically no building alterations, assuming that the room has previously been equipped with a grill for a fuel burning air furnace. Furthermore, the walls of the room need not be wired since connections are made in the basement. All 100 the advantages of economical operation are secured by the air circulation feature.

We claim:

1. An electrical device for heating air within a room of a building comprising a 115 register opening into said room, a housing located a substantial distance below the floor of said room, an electrical heating element within said housing, and a plurality of extended passageways connecting said register 120 and housing, one of said passageways serving to conduct a hot upwardly moving current of air from said housing to said room, and another of said passageways serving to conduct a downwardly moving current of 125 cool air from the room to the housing, said downward current being induced solely by said upward current.

2. An electrical device for heating air within a room of a building comprising a 130

- register opening into said room, a housing located a substantial distance below the floor of said room, an electrical heating element within said housing, and an extended conduit connecting said register and housing, said conduit having at least two passageways, one of the passageways serving to conduct a hot upwardly moving current of air from the housing to the room, and another 5 of said passageways serving to conduct a downwardly moving current of cool air from the room to the housing, said downward current being induced solely by the upward current.
15. 3. An electrical device for heating air within a room of a building comprising a register opening into said room, a housing located adjacent a floor below said room, an electrical heating element disposed within 20 said housing, a plurality of extended passageways connecting said housing and register, one of said passageways serving to conduct a heated upwardly moving current of air from the housing to the room, said current of air being caused solely by said heating element, and another conduit serving to conduct a downwardly moving current of air from the room to the housing, said downwardly moving current being induced solely 25 by said upwardly moving current.
4. An electrical device for heating air within a room of building comprising a register opening into said room, a housing located a substantial distance below the level 30 of the floor of said room, a plurality of flues defined by the walls of said housing,
- said flues communicating with each other adjacent the bottom of the housing, an electrical heating element disposed within one of said flues, and an extended conduit connecting said register and housing, said conduit having a plurality of separate passageways for conducting a heated upwardly moving current of air from said one flue to said room and for conducting a downwardly 40 moving cool current of air from the room to another flue of the housing, said currents of air being caused solely by said heating element.
5. An electrical device for heating air 45 within a room of a building comprising a register opening into said room, conduit extending downwardly from said register, said conduit having a plurality of passages, said passages opening thru one side of said conduit near the lower portion of the same, a housing secured to said one side of said conduit, said housing having an upstanding inner wall serving to define a passage communicating with one passage of the conduit, another portion of said housing being in communication with another passage of said conduit, and electrical heating means positioned within said housing and serving to effect downward and upward movement 55 of air thru said conduit and circulation of air thru said housing.

In testimony whereof, we have hereunto set our hands.

ARTHUR J. KERCHER.
WILLIAM WESLEY HICKS.
